Patented Mar. 22, 1921.

FIG. 3

Inventor
Jordan Christoff
By B. J. Mager atty.

UNITED STATES PATENT OFFICE.

JORDAN CHRISTOFF, OF EPSOM, AUCKLAND, NEW ZEALAND.

PROPELLER FOR STEAMSHIPS.

1,372,402.

Specification of Letters Patent. Patented Mar. 22, 1921.

Application filed September 10, 1919. Serial No. 322,968.

To all whom it may concern:

Be it known that I, JORDAN CHRISTOFF, subject of the King of Great Britain, residing at Epsom, Auckland, in the Dominion of New Zealand, have invented a new and useful Improved Propeller for Steamships; and I do hereby declare the following to be a full, clear, and exact description of the same.

10 This invention has been devised with the object of providing improved means for use in the propulsion of steam or other power driven ships, and it consists in a special form of propeller and manner of actuating it, by which a greater propulsive force is obtained than is obtained by the use of the ordinary rotating screw propeller.

According hereto the propeller is formed by a number of blades that are hinged or 20 knuckled to a suitable head that is carried on the outer end of a shaft extending horizontally through the ship's stern and to which a longitudinal reciprocating motion is imparted by the vessel's engines. This 25 motion is designed, and the blades are so mounted, that on their outward travel relatively to the ship's stern, they will open out to assume a position at right angles to the line of their shaft, and on their inward 30 travel they will turn in to lines parallel with the shaft. Consequently, therefore on their outward movement they will present the full area of their faces to the water thus obtaining a rearward push thereon that will 35 send the ship forward, and on their inward movement will present their edges to the line of travel thereby presenting a minimum of resistance to the water.

Any desired number of propellers, thus 40 constructed and operated may be arranged upon the stern of the ship. For most purposes however, a convenient arrangement is to employ two propellers, arranged one on each side of the ship's rudder and working 45 in alternation to balance the driving power, or in unison with one another if so desired. Such an arrangement as applied to two bladed propellers is shown in the accompanying drawings, illustrating the invention.

50 These drawings are mainly of diagrammatic form to show the general features governing the construction and operation of the propellers. These features in their details of construction may be varied in quite a number of ways to suit different circum-

stances, and it is to be understood that the invention is not confined to such details of construction as are shown in the drawings.

Referring to the drawings:

60 Figure 1 is a side elevation, the ship's stern being indicated by dotted lines.

Fig. 2 a plan of the propulsive means.

Fig. 3 is a detail inner face view of one 65 of the propellers.

Fig. 4 is a rear elevation of an alternative construction of propeller.

In carrying out the invention each propeller is formed by a pair of blades A—A', each formed of approved area and thickness 70 of material and generally of oblong form. These blades are made of metal, either cast or wrought and suitably strengthened. Each blade is hinged along one of its edges to a head B by hinges C that are positioned 75 so that the two blades extend vertically on the respective sides of such head. The two blades are therefore capable of turning to lie parallel with one another, or to turn outward to extend in the same plane. In each position they engage stops formed on the head that keep them from folding right in together and also keep them from turning out beyond the line in which they occupy 80 the same plane.

85 The head B is supported to slide upon a guide bar D fixed to extend from the ship's stern. This bar is shown as arranged to extend rearward from a suitable stuffing box fitting E arranged on such stern. Passing 90 through the said stuffing box are a pair of sliding rods F that together form the propeller shaft and at their outer ends, are fixed to the head B and at their inner ends, inside the ship, are attached to a slide head G carried in horizontal guides H and adapted to be moved reciprocally in such guides by means of a connecting rod J and crank K mounted on a shaft M that receives rotation from the ship's engines. By these means, 95 the head B is moved reciprocally along the guide bar D, the blades A—A' opening outward on the rearward movement of the head and closing in, on the forward movement in order to exert the propulsive force in the 100 manner before described.

105 In the arrangement shown in the drawings, two propellers are provided and disposed on respectively opposite sides of the ship's rudder. They are also so driven relatively to one another that they will work in alternation, *i. e.*, while one is moving rear-

ward and exerting its propulsive force, the other is moving idly forward. This will balance the driving shaft M in its rotation.

The same principle of construction and operation may be adapted to a propeller formed with more than two blades such blades in such a case being disposed to extend radially from the head B and being hinged or knuckled at their inner ends to such head so as to be capable of turning in to lie in planes parallel with the shaft or of turning out to extend in planes at right angles with such shaft. Such a construction as applied to a three bladed propeller is shown in Fig. 4.

15. The angles at which the propellers work may be varied if so desired, for instance they may be disposed to incline outward from the line of the ship's hull similarly to the slight outward inclination generally given to the shafts of twin screw propellers. The propellers may also, if so desired, be adapted to operate independently of one another in order to assist in the steering or maneuvering of the vessel.

20. 25. I claim:—

1. In combination, a guide shaft, a head mounted for longitudinal movement on the guide shaft, rods attached to the head and

30. mounted for reciprocatory movement parallel with the guide shaft, and blades hinged to the head.

2. In combination, a guide shaft, a head mounted for longitudinal movement on the guide shaft, blades hinged to the head, rods attached to the head and arranged for reciprocatory movement parallel with the guide shaft, a crosshead connecting said rods, guides for the crosshead, a crank shaft, and a rod connecting the crank of said shaft with the crosshead.

3. In combination, a pair of guide shafts, a head mounted on each guide shaft for longitudinal movement, blades hinged to each head, rods attached to each head, crossheads, for the rods, guides for the crossheads, a shaft having cranks arranged in angular relation, means to operate said crank shaft, and rods connecting the cranks of said shaft to the crossheads.

In testimony whereof, I have signed this specification in the presence of two subscribing witnesses.

JORDAN CHRISTOFF.
